UNITED STATES PATENT OFFICE.

GEORGE M. BEARDSLEE, OF CHICAGO, ILLINOIS, ASSIGNOR TO BEARDSLEE CHANDELIER MANUFACTURING COMPANY, A CORPORATION OF DELAWARE.

LIGHTING-FIXTURE.

1,297,781.

Specification of Letters Patent. Patented Mar. 18, 1919.

Application filed August 28, 1917. Serial No. 188,563.

To all whom it may concern:

Be it known that I, GEORGE M. BEARDSLEE, a citizen of the United States, and a resident of Chicago, in the county of Cook and State 5 of Illinois, have invented certain new and useful Improvements in Lighting-Fixtures, of which the following is a description, reference being had to the accompanying drawings, which form a part of my specification.

10 My invention relates to lighting fixtures more especially adapted to the employment of electric lamps of high candle power and particularly where the lamps, shades and bowls are intended to be suspended by a 15 chain or other medium from a stud in the conduit-box or supporting member.

15 The invention contemplates means whereby the relation between the lamp and the shade or bowl, or both, may be readily adjusted or altered, so as to produce the desired lighting effect, without dismantling or disconnecting any of the parts of the fixture.

20 The invention also contemplates a construction which readily enables the suspended 25 bowl to be partially disconnected from its suspending means, (without entirely dismantling the fixture) so as to permit the bowl and inclosed portion of the fixture to be easily cleaned and the lamp or lamps 30 to be replaced if necessary.

25 The invention provides a fixture which permits such adjustment of its respective 35 parts that all direct rays of light, especially when high candle power lamps are employed, may at all times be prevented from 40 passing beyond the shades and bowls, so as to adapt them to all purposes, without, however, encountering the harsh rays of light and yet at the same time eliminating the objectionable shadows frequently encountered 45 with a suspended type of fixture.

50 The foregoing enumerated advantages, as well as others inherent in the invention, will be more fully comprehended from the following detailed description of the accompanying drawings wherein:—

Figure 1 is a vertical sectional view of a lighting fixture embodying my improved features.

55 Fig. 2 is a cross-sectional view, taken on the line 2—2 of Fig. 1 looking downwardly, with portions of the shade broken away.

Fig. 3 is a detail perspective view of the lamp-socket holding member.

Fig. 4 is a detailed perspective view of an 55 adjusting element adapted to coöperate with the lamp-socket holding member.

Fig. 5 is a partial vertical view and side elevation of a modified form of lighting fixture embodying my invention. 60

Fig. 6 is a fragmentary detail view of my improved supporting element and the lower portion of the surrounding canopy or shell shown in Fig. 5.

Figs. 7 and 8 are detail perspective views 65 of my improved bowl-supporting elements or clips.

Fig. 9 is a vertical sectional view of a modified form of shell provided with my improved bowl-supporting member or holder. 70

Fig. 10 is a bottom plan view of same.

In the exemplification of the invention as illustrated in Fig. 1, the lighting fixture is shown supported by means of a chain suspended from a supporting stem, and also 75 provided with a large shade and bowl which may be adapted to direct and soften the rays of light emanating from a high candle power lamp, illustrated at 20, which screws into the usual porcelain socket member 21. The 80 member 21, in this instance, is secured to the laterally disposed flange 22 at the lower end of a supporting member 23, the upper end whereof is preferably provided with an oblong opening extending transversely there-through so as to give it the appearance of a loop or link of a chain, as very clearly shown in Figs. 1 and 3. The lower end of member 23 may be somewhat differently formed from that shown, so as to receive the porcelain top 85 or screw-cap of any standard make of electric lamp-socket. The portion of the member 23, intermediate of the oblong opening at the upper end and the transversely disposed flange 22, is externally threaded, as clearly 90 shown, so as to receive the internally threaded collar or bushing 24, shown in detail in Fig. 4.

One side of member 23 is provided with a longitudinally disposed groove 25 extending 100 from the oblong opening down to the lower end of member 23, thus providing a continuous passage from the opening at the upper end of the lamp-receiving socket 21 to the upper end of members 23 for the passage 105 of the conductors or electric wires 26, as shown in Fig. 1. The slot or groove 25 is made of sufficient depth to receive the elec-

tric cords or wires 26, and securely embed the same without interfering with the adjustable collar 24; the slot or groove 25 being preferably made substantially U-shape in 5 cross-section, as shown in Fig. 2.

The electric conductors or wires 26, which are usually entwined about the supporting element or chain portion of the fixture, enter the oblong hole at the upper end of the member 23 from the side opposite to that provided with the slot or groove 25, and are passed down through the slot, as shown in 10 Fig. 1, to the lamp-receiving socket where they are secured to their respective terminals in the usual manner.

The loop-portion of member 23 receives the adjacent loop or link of the supporting chain, indicated at 27; the chain being of a well known construction, with the uppermost 20 loop or link of the chain passing through an oblong hole or opening in the lower end of my improved supporting stem or member 28. The lower end of supporting member 28, like the upper end of member 23, by reason 25 of the oblong opening, is given the appearance of a loop or link of a chain, and also provides means for the passage of the electric conductors or wires 26. The supporting stem 28 is preferably in the nature 30 of a solid rod with the lower end somewhat reduced like the upper end of member 23, and provided with the oblong hole, as shown at 29; and one side of the rod or member 28 is provided with a longitudinally disposed 35 groove or socket 30 which extends to a point near the upper end of the member 28, where it terminates in the transversely disposed oblong hole 31, and thus provides a passage for the electric conductors or wires 26, which 40 pass out through the upper end of the stem or member 28 into the conduit-box 32 and are there attached to the ends of the service wires which terminate in the conduit-box 32.

The upper end of the supporting member 45 28 is shown terminating in an annular shoulder 33 which is preferably internally threaded so as to enable the stem or member 28 to be screwed onto a threaded stud 34 formed in or secured within the conduit-box, as 50 shown in Fig. 1. The stem or member 28 is preferably made round in cross section and of a length sufficient to extend from its attaching point in the conduit-box through the lower end of a suitable canopy or shell, 55 illustrated at 35, which is adapted to encircle the opening in the wall or ceiling where the conduit-box is located. The canopy 35 may be secured to the supporting stem or member 28 in any suitable manner; Fig. 1 disclosing 60 a construction wherein the supporting stem or member 28 has its lower end externally threaded so as to receive a suitable ring and clamp nut, as indicated at 36 in Fig. 1.

As is evident from the construction shown 65 and described, the oblong holes and longitudi-

nally disposed groove or slot in the supporting stem or member 28 provide suitable passage for the electric wires or conductors without in any way subjecting them to improper action by, or frictional contact with, 70 the incasing elements, and thus properly conceal the electric wires, except at a point intermediate of the upper canopy or shell and the lamp-supporting member 23.

The bushing or collar 24, which is adapted to screw onto the lower stem member 23, is provided with an annular shoulder 37 and with a laterally projecting lug or lip 38 preferably at a point above the annular shoulder 37. The shoulder 37 is adapted to provide 80 support for the annular holder or shell 39. The lower end of the holder 39 is flared or flanged, as shown at 40, so as to adapt it to engage with the inner surface of the shade 41; the annular shell or holder 39 being arranged to pass through the neck of the shade as shown. My improved shell or holder 39 is provided at its top with an opening for the passage of the bushing or collar 24, and one side is provided with a slot extending 90 from top to bottom, as shown at 42 in Figs. 1 and 2, thus splitting the shell from top to bottom. The slot is of a width sufficient to receive the lug or lip 38, as shown in Fig. 1, and also permits the passage of the upper 95 end of member 23 or link of chain 27. The slot 42, in the shell or holder 39, enables the shell to be inserted edgewise onto the supporting chain, so that the shell or holder 39 and the shade 41, as well as the bowl 43, may 100 be readily removed without any further disassembling of the fixture proper; it being understood, of course, that the holder 39 and shade 41 must first be put into place before the lamp 20 has been put into place.

The lower end of the shell 39 and outer surface thereof is provided with an annular channel which is preferably formed by curling or turning up the lower edge of the shell on the outside of the shell, as shown at 44. 110 This provides a channel for a split ring 45 of spring wire which is preferably adapted to extend entirely about the shell; the ring 45 being preferably composed of spring wire so as to enable the same being collapsed or compressed for the purpose of inserting it into the channel or removing it therefrom when desired. The curled flange or channel portion of the shell 39 is provided with slots 46 at equi-distances apart; the slots 46 being of sufficient dimensions to expose portions of the split ring or spring wire 45, as shown in dotted lines in Fig. 2, and to the left in Fig. 1. The slots 46 in the lower part of the shell 39 are adapted to receive the hooks 47 at 120 the upper ends of supporting elements 48, which may be either in the nature of rods or chains, and whose lower ends are suitably formed to support the globe 43.

When it is desired, and in order to give 130

a more finished appearance to the fixture, a collar 49 may be provided adapted to fit snugly at its upper end about the shell or holder 39, while its lower end is enlarged or flared so as to incase the upper end or neck of the shade 41; it being understood, of course, that this collar must be placed on the shell or holder 39 before the latter has been put into place.

10 With the fixture assembled as hereinbefore described, the shade and globe may then be adjusted relative to the lamp, or rather the lighting element of the lamp, so that the direct rays of light, especially where high 15 candle power lamps are employed, may at all times be kept within the shade and bowl so as to adapt the fixture to all purposes without permitting the escape of harsh rays of light, while at the same time obviating 20 any objectionable shadows.

As is evident from the construction shown and described, namely with the rib or lug 38 seated in the slot 42 of the shell 39, the mere rotation of shell 39 about member 23 will 25 cause the shade and globe or bowl 43 to be raised or lowered depending upon the direction in which the shell or holder 39 is rotated, so that the lighting element of the lamp 20 may be brought into a plane below 30 the horizontal plane of the top of the bowl 43; the relative position of the lamp may be quickly adjusted or altered without necessitating any changes or disassembling of the fixture or its respective parts.

35 In the construction illustrated in Fig. 1, the bowl is shown suspended from the shell or holder 39 by rods 48, the lower ends whereof are bent into hook form so as to extend through suitable openings 50 formed 40 in the bowl, as the bowl in this construction is formed without any attaching flange or rim at the upper edge thereof.

In Fig. 5, I show a modified form of my invention as well as illustrating a slightly 45 different style of fixture. In this construction the canopy 35 is similar to that shown in Fig. 1, except that the lower end is provided with a slip-ring 51 provided with a set-screw 52, shown in detail in Fig. 6, and 50 providing a well known construction whereby the canopy is secured up into place onto the supporting member or stem 28^a, which, so far as general construction is concerned, may be identical with the member 28 shown 55 in Fig. 1, with the exception that the stem or member 28^a need not be externally threaded because the set-screw 52 of the slip-ring 51 will maintain the canopy in position.

The stem or member 28^a, like member 28, 60 is intended to be provided with the longitudinally disposed groove 30 extending from a point adjacent the upper end thereof down to the lower reduced end which is provided with the oblong slot 29 and which gives it 65 the appearance of a link or loop of a chain,

adapted to receive the uppermost link 27 of the supporting chain or other supporting element that may be employed.

The attaching element 23 is shown similar in construction to that illustrated in Fig. 1, 70 being externally threaded on its rounded surfaces and provided with a longitudinally disposed groove for the passage of the conductors or electric wires 26; the attaching element 23 being shown also provided with 75 a laterally extending flange to which the lamp-socket 21 is secured in any suitable manner. The attaching element 23 is provided with a bushing or collar 24 which is internally threaded and screws lengthwise 80 of member 23, as previously described; the bushing or collar being provided with an annular shoulder which provides suitable support for the shell or holder 39 and which latter is provided with a slot-way 42, similar 85 to that previously described and shown in Figs. 1 and 2, which enables the shell or holder 39 to be slipped onto the upper reduced end of member 23 after the lamp-socket has been put into place; and this slot 90 42 also receives the lug or lip 38 formed on the bushing or collar 24 so that the latter will be screwed lengthwise of member 23 when the shell or holder 39 is rotated. The lower end of the shell 39 is curled upward, 95 as previously described, so as to provide an annular channel in which is placed the split-ring or spring-wire 45. The curled lower end of the shell 39 is provided at equi-distances apart with slots 46 adapted to receive 100 the upper hooked ends of the supporting elements shown in the nature of chains 48 in Fig. 5.

In the fixture illustrated in Fig. 5, no shade is employed and a different style bowl 105 53 is shown, the latter being shown partially in section and partially in elevation.

The upper end of the bowl 53 is provided with an outwardly flared attaching rim so as to produce an annular groove at 110 54 adapted to receive an encircling wire or ring 55. The wire or ring 55 is provided with a suitable number of angular members or clips shown in detail in Figs. 7 and 8; the members or clips comprising the hopper body portion 115 56 provided with a hole 57 for the reception of the hook of the attaching element or chain 48; while the lower part of each member or clip is shown bifurcated, with the bifurcations terminating in the hub-portions 57^a, 120 57^a provided with openings extending lengthwise therethrough for the passage of the ring or wire 55. The attaching clip or member shown in Fig. 7 is intended to receive the ends of the ring or wire 55; the 125 ends of the wire being passed through the openings in the hub-portions 57^a, 57^a and then bent in the angular manner shown so as to prevent the withdrawal of the wire. The clip or member shown in Fig. 8 is sub- 130

stantially similar to that shown in Fig. 7, with the exception that the portion of the metal intermediate of the bifurcations is not entirely cut away but is left to provide the 5 tongue 58, which is preferably given a slight twist so as to have the flat faces thereof presented in the direction of the bifurcated ends of the attaching clip or member. The attaching elements or members are given the 10 angular formation shown in Figs. 7 and 8 in order that they may extend over the top of the flange or rim of the bowl, as shown in Fig. 5; and in the fixture illustrated, two of the clips or members are like that 15 shown in Fig. 8, while the third is like that shown in Fig. 7. The wire or ring 55 is provided with a suitable number of the attaching elements or members, like that shown in Fig. 8, before the attaching element 20 shown in Fig. 7 is secured in place; in other words, the ring or wire 55 is provided with attaching elements or members, like those shown in Figs. 7 and 8, corresponding in number with the supporting 25 chains or rods 48, as, for example three in number, arranged at equi-distances apart. After the attaching elements or members shown in Fig. 8 have been slipped onto the wire or ring 55 and placed at the proper 30 point, the tongues 58 are given sufficient twist, thereby slightly bowing or bending the wire 55, as shown at 59 in Fig. 8, which will prevent any shifting of the attaching element or member lengthwise of the wire 35 or ring, thus maintaining the members in proper position. The ends of the wire or ring 55 are not bent about the bifurcations of the member or clip shown in Fig. 7, until after the ring with its spaced attaching 40 members or elements has been properly placed about the bowl. The supporting elements or chains 48 are then hooked through the perforations 57 in the upper ends of the members, thereby supporting the bowl in 45 position.

When it is desired to clean the fixture and the interior of the bowl, merely one of the rods 48 need be unhooked from the attaching member or clip which allows the bowl 50 to swing downwardly into the position shown in dotted lines in Fig. 5; the tongues 58 of the clips or attaching members, together with the slight buckle or bend in the ring or wire, preventing any change in the 55 relative position of the respective parts.

Where my improved fixture is intended to be used in connection with a single bowl, the lamp may be provided with a reflector 60 which is slipped onto the neck of the 60 lamp before the latter has been screwed into its socket, thereby cutting off the upward rays of light from the lamp and enabling them to be confined within the bowl through the proper adjustment of the holder, and

therefore also of the bowl, lengthwise of 65 the attaching element 23, so that the lighting element of the lamp will come below the horizontal plane of the upper edge of the bowl, with the result that all of the direct rays of light will be properly reflected and 70 diffused to a desirable degree and at the same time provide a shadowless unit without exposing the reflector to view.

The reflector 60 is shown somewhat funnel-shape; being provided with proper flare 75 and desired curvatures, with the reduced top or end being preferably formed with suitable slits, thus enabling the reflector to receive the reduced end or neck of the lamp and have frictional engagement therewith. 80

It is evident from the construction shown that the reflector 60 may be adjusted on the neck of the lamp so as to catch all upward rays of light and reflect them downwardly into the bowl of the fixture. With a proper 85 adjustment of holder 39 on member 23, thereby adjusting bowl 53 relative to the lamp, and with a proper placing of reflector 60, the rays of light are so reflected as to provide a shadowless unit; the rays 90 being confined within the bowl so that no direct rays are allowed to escape.

In Figs. 9 and 10 I illustrate a modified form of my invention wherein the bowl holder in modified form is shown secured 95 to a well known type of shell 61, the latter being shown in section with the upper end broken away, while the lower flanged end is provided with the usual set screws 62 placed at equi-distances apart, as more clearly 100 shown in Fig. 10; the screws 62 being adapted to engage with the outwardly flared rim 63 of the holder 64. The lower edge of the holder is curled upwardly, as shown at 65 in a manner similar to the holder 39 so 105 as to provide an annular channel adapted to receive the split ring or wire 66 which may be similar to the split ring 45 shown in Fig. 1. The holder 64, like holder 39, has the lower flanged end provided with the vertically disposed slots 67 which expose portions of the split ring or wire 66, as more 110 clearly shown in Fig. 10; the slots being adapted to receive the upper hooked ends of the suspending elements or rods 48 115 whereby the bowl or globe is suspended in place.

It is evident from the constructions shown and described that the element which I have termed a holder, and as disclosed in 120 Figs. 1 and 5, is adapted to carry two pieces of glass, to-wit the shade and the bowl, so that the entire weight of these two members will be on the holder; it being understood also that instead of employing suspending 125 elements in the nature of rods 48, chains may be employed. It is clearly evident from the constructions shown and described

that the fixture may be readily adjusted to different sizes of lamps without necessitating any rearrangement or alteration of the parts of the fixture; the adjustment being obtained by simply rotating the holder on the stem or rod element 23; furthermore, it is apparent from the construction shown that with the shade put into place on the holder, the chains or rods, whereby the lower bowl is suspended, will be locked in place on the split ring in the holder, thus preventing any accidental removal of the suspending element or rods through the application of upward pressure on the bottom of the bowl.

I have shown and described what I believe to be the simplest and best embodiments of my invention, but it is evident that the invention may have embodiment in different mechanical form without, however, departing from the spirit of the invention.

What I claim is:

1. In a lighting fixture, an electric lamp-socket holding member or stem provided with an opening extending transversely through the upper end thereof and an attaching flange at the lower end, while the outer surface of said stem intermediate of said opening and the flange is screw-threaded, internally threaded means adapted to encircle said member or stem and screw lengthwise thereof, and a shell or holder provided with an opening in its top for the passage of said stem or member, the holder and said means being provided with interlocking surfaces whereby rotation of the one will be imparted to the other and adjustment of the holder lengthwise of said member or stem obtained.

40 2. A lighting fixture, comprising a holder or shell, the lower end whereof is provided with a channel provided with slots at predetermined distances apart disposed transversely of the channel, a split ring or member mounted in said channel and disposed across said slots, and bowl-suspending means adapted to extend into said slots and engage with said split ring or member.

3. In a lighting fixture, a lamp-socket holding member or stem provided with a wire-receiving groove extending lengthwise thereof and terminating at its top in an attaching end and at its bottom in an electric lamp-socket attaching flange, the stem being threaded intermediate of its ends, a holder or shell provided with an opening in its top and split from top to bottom so as to permit the insertion of said member or stem edgewise through the split portion of the shell or holder, and means adapted to screw lengthwise of said member or stem and have supporting relation with the inside of said holder or shell, said means being provided with an extension or lip adapted to

engage in the split portion of the shell or holder whereby the shell or holder and said means are locked against independent rotation and adjustment of the latter relative to the lamp-socket permitted.

4. A lighting fixture, comprising a lamp-socket holding member or stem provided with screw-threads and with a wire-receiving groove extending from end to end and terminating at its top in an attaching end, a member threaded on said first member or stem so as to be adjustable lengthwise thereof, a holder or shell provided with an opening in its top for the passage of said first member or stem and arranged to have interlocking relation with said second member whereby rotation of said shell or holder will cause said second member and said holder to move lengthwise of the first member or stem, said shell or holder being provided with a channel at the lower end thereof, the channel being provided at predetermined points with slots extending transversely of the channel, a compressible ring mounted in said channel so as to extend across said slots, and bowl-suspending means adapted to extend through said slots and engage with said compressible ring.

5. In a lighting fixture, a one piece supporting member or stem provided with an annular threaded socket at the upper end thereof, openings extending transversely through the stem adjacent the upper end and at the lower end and provided with a conductor wire-receiving groove extending lengthwise of the stem from opening to opening, the stem being externally threaded intermediate of said openings, and shell-supporting means threaded on said stem whereby a shell may be adjusted relative to the ends of the stem.

6. In a lighting fixture, a one piece supporting member or stem provided with a threaded socket at its upper end, oblong holes extending transversely therethrough adjacent the upper end and at the lower end, a conductor wire-receiving groove disposed lengthwise of the stem from opening to opening, the lower end of said stem being screw-threaded, and means adapted to screw onto the threaded portion of said member or stem, in combination with a canopy or shell adapted to fit about said member or stem and be held in place by said means.

7. A lighting fixture, comprising a one piece supporting member or stem provided with a conductor wire-receiving groove extending lengthwise of the stem and provided with openings extending transversely of the stem adjacent both ends thereof, a lamp-socket holding member or stem adapted to be suspended from said first mentioned member or stem, said lamp-socket holding member being externally threaded and provided with

a conductor wire-receiving groove extending lengthwise thereof, and a shell or holder having adjustable relation with said socket-holding member or stem so as to be adjustable lengthwise thereof.

8. In a lighting fixture, a one-piece supporting stem provided with a threaded socket at its upper end and with a wire-receiving groove extending lengthwise thereof and terminating at both ends in openings extending transversely through the stem, and a ring adjustable lengthwise of the stem.

9. In a lighting fixture, a bowl-encircling band, and members or clips, each provided with bifurcations at one end having openings for the passage of the band, while the open end is angularly disposed and provided with suspending means receiving opening, said clips being each provided with an apertured tongue, disposed intermediate of the bifurcations, having a band-receiving opening, the tongues being flexible to permit twisting so as to dispose them tangentially to the encircling band and form binding relation therewith.

10. In a lighting fixture, a bowl encircling band, and members or clips provided with bifurcations having openings for the pas-

sage of the band and with flexible, apertured tongues disposed intermediate of said bifurcations and adapted to be twisted at an angle to the bifurcations so as to form gripping relation with the band.

11. A lighting fixture, comprising an electric lamp-socket holding member, a bowl-supporting holder adjustable lengthwise of said member, and a downwardly and outwardly flared reflector arranged to have frictional engagement with the upper end of the electric lamp and adapted to reflect upward rays of light into the bowl.

12. In a lighting fixture provided with a suspended bowl, an electric lamp-socket holding member, bowl-supporting means adjustable lengthwise of said lamp-socket member whereby the bowl may be adjusted relative to the lamp, and a reflector provided with an upwardly presented slit portion through which the electric lamp passes, said reflector having frictional engagement with the electric lamp and adapted to reflect the upward rays of light into the bowl.
